UNITED STATES PATENT OFFICE.

SWAN TEVANDER, OF MAYWOOD, ILLINOIS, ASSIGNOR TO AMERICAN CAN COMPANY, OF NEW YORK, N. Y., A CORPORATION OF NEW JERSEY.

MACHINE FOR ATTACHING BAIL-EARS TO SHEET-METAL PAILS OR VESSELS.

1,072,790.

Specification of Letters Patent.

Patented Sept. 9, 1913.

Application filed November 18, 1907, Serial No. 402,623. Renewed March 15, 1913. Serial No. 754,646.

To all whom it may concern:

Be it known that I, SWAN TEVANDER, a citizen of the United States, residing in Maywood, in the county of Cook and State of Illinois, have invented a new and useful Improvement in Machines for Attaching Bail-Ears to Sheet-Metal Pails or Vessels, of which the following is a specification.

My invention relates to improvements in machines for attaching bail ears to sheet metal pails or vessels.

The object of my invention is to provide an automatic machine which will feed the bail ears one by one from a hopper or receptacle containing them in bulk, and attach them to the bodies of the pails or vessels to which they are to be applied and produce liquid tight closures or joints between the bail ear and pail body.

My invention consists in connection with coöperating bail ear attaching dies mounted respectively upon a stationary horn and upon a reciprocating slide or plunger, of a feed chute for the bail ears, a feed slide for moving the bail ears one by one into position for attachment to the pail body, and an inclined rotatable hopper having orifices at its bottom edge or rim for the bail ears to pass through and by which the bail ears are automatically fed one by one to the feed chute and feed slide.

My invention also consists in the novel construction of parts and devices, and in the novel combinations of parts and devices herein shown and described.

In the accompanying drawing forming a part of this specification, Figure 1 is a front elevation of a bail ear attaching machine or press embodying my invention. Fig. 2 is a detail central vertical section on line 2—2 of Fig. 1. Fig. 3 is a detail plan view partly in horizontal section showing the bail ear feed slide. Fig. 4 is a detail vertical section on line 4—4 of Fig. 2. Fig. 5 is a detail vertical section showing the bail ear in the lower die before it is seamed to the body of the pail. Fig. 6 is a detail section of the bail ear feed device on line 6—6 of Fig. 1, one half of the cover M² hereinafter described being broken away to better show other parts. Fig. 7 is a detail section on line 7—7 of Fig. 6. Fig. 8 is a detail vertical section through the upper and lower bail ear attaching dies and showing the bail ear in the dies seamed to the body. Fig. 9 is a detail vertical sec-

tion on line 9—9 of Fig. 1 showing the feed valve for the shellac or liquid packing and Fig. 10 is a detail sectional view showing the bail ear after it is attached to the pail body with the shellac or liquid packing interposed between the folds of the seam which unites the bail ear to the body.

In the drawing, A represents the frame of the machine, B the horn which supports the lower die, C the reciprocating slide which carries the upper die, D the lower clenching or seaming die, the same having an outer movable member D¹, F the upper or reciprocating clenching or seaming die carried upon the reciprocating slide or punch C, G the feed slide for the bail ears, H the feed device or valve for the shellac or liquid packing, and H¹ the reservoir or vessel containing the same.

M is the feed chute for the bail ears and N the rotary feed hopper for the bail ears.

The pail body X is furnished with an opening X¹ surrounded by a seaming flange x. The bail ear X² is furnished with a base flange x¹ and with a cap X³ having a seaming flange x². The bail ear X² and cap X³ are first assembled together, and the seaming flange on the cap slightly contracted so as to hold the bail ear X² and the cap X³ together. The bail ear and cap thus assembled are first fed into the lower die on the horn, as shown in Fig. 5, and then the pail body is inserted over the horn in position to receive the bail ear, and then the upper die F depresses the movable member D¹ of the lower die, thus projecting the bail ear through the opening in the pail body and assembling the bail ear and cap with the pail body into position for clenching or seaming the same together, the further downward movement of the reciprocating slide or punch which operates the upper die, then actuates the shellac or packing feeder H and causes the requisite amount of shellac or liquid packing to be fed into the joint or seam before the flanges or folds thereof are closed or compressed together by the further downward movement of the upper die which then takes place. The horn B is secured to the frame A by bolts b.

The reciprocating slide C which actuates the upper die is moved up and down in its guides C¹ by a crank C² on the main driving shaft K which is journaled in suitable bearings A¹ on the frame of the machine, and furnished with a drive wheel K¹. The

main or central portion D of the lower die has a stem d fitting in a suitable socket in the horn B, and secured thereto by set screws b¹, and is furnished with a central channel d¹ and branch channels d² through which the shellac or liquid packing is supplied to the seaming flanges of the bail ear, bail ear cap and pail body. The outer or surrounding portion D¹ of the lower die is furnished with a central socket or die cavity d³ receiving and surrounding the main portion D of the lower die, the upper portion of this cavity also serving to receive the bail ear, as will be readily understood from Figs. 4 and 5 of the drawing. The outer or surrounding portion D¹ of the lower die is mounted movably on the main portion D and is held in position by a coiled spring D² which surrounds the stem d of the die D and bears against a stuffing box nut D³ secured to the movable member D¹ of the die. The packing D⁴ of the stuffing box prevents escape of the shellac or liquid packing from the die cavity d³ of the die member D¹. The horn B is furnished with a feed passage b² connecting with the feed passage d¹ and stem d of the lower die D, and with the feeder H through suitable connecting pipes h. The shellac or liquid packing feeder H preferably consists of a movable or reciprocating valve a valve shell h¹, connecting with the feed pipes h leading to the lower seaming die and with the shellac or liquid packing reservoir H¹ through a connecting pipe h². The feed valve H is preferably held normally closed by a spring H², and it is preferably automatically opened, so as to feed or supply the requisite amount of shellac or liquid packing to the seam joint before the flanges thereof are closed or pressed together, from the reciprocating slide of the upper die by a connecting rod or strap h³ secured to said slide, having an eye h⁴ surrounding the stem of the valve H and engaging a pin h⁵ thereon.

The bail ear feed slide G is mounted to reciprocate in suitable guides g, and is preferably actuated at suitable intervals as required in one direction by a spring g¹ and in the opposite direction by an incline or cam g² on the reciprocating slide C of the upper die F, which engages a roller g³ on a crank arm or lever g⁴ having a shaft pivot g⁵, and is connected by a link g⁶ with the bail ear feed slide G. The bail ears with their caps assembled thereon are delivered in front of the feed slide G by a chute M, and the feed slide G is preferably furnished with a curved cavity g⁷ on the edge thereof adjacent to the chute, so that as the feed slide is moved forward it will permit the bail ears in the chute to slightly descend, and so that when the feed slide moves backward it will force the column of bail ears in the chute slightly upward; this movement

of the column of bail ears in the chute tending to prevent sticking and insuring certainty and regularity of feed.

The feed chute M has at its upper end a circular or disk-like extension M¹ which constitutes the stationary bottom of the rotary feed hopper N, and this disk-like extension M¹ of the feed chute is furnished with a circularly curved segmental rib or guide m forming a curved passage or chamber m¹ at the lower side of the rotary cylindrical hopper N to receive the bail ears as they issue from the rotary hopper.

The circular or disk like extension M¹ of the feed chute M is also furnished with a hollow central stud m² which serves as a bearing for the shaft N¹ of the rotary hopper N. The rotary inclined cylindrical hopper N is furnished at its lower edge or rim with a series of openings n for the bail ears to pass through into the curved chamber or passage m² of the feed chute M.

The rotary inclined cylindrical hopper N is connected to its operating shaft N¹ by a spider N² having a hub N³ secured to the shaft N¹. The spider N² has a marginal rim or flange N⁴ embracing the upper end of the hopper N and to which the hopper is secured. The hopper N is continuously rotated by means of a pulley N⁵ on its shaft N¹ through a belt N⁶ passing around an idler pulley N⁷ and a driving pulley K² on the driving shaft K.

The inclined stationary bottom M¹ of the rotary feed hopper N is furnished with a movable or yielding cover M² which is preferably hinged at m³ to the feed chute M so that this cover by opening or yielding may prevent the bail ears from becoming stuck or jammed in the curved connecting passage m² of the chute M. The cover M² extends over the segmental pocket M¹ on both sides of the chute M, but is shown in Fig. 6 as broken away on one side in order to disclose the parts beneath this cover. The curved connecting passage m² of the feed chute M is also preferably furnished with a yielding arm or gate m⁴ at its lower end adjacent to the upper end of the feed chute M so that a bail ear may be forced out through this yielding gate in order to prevent clogging or jamming when necessary. The bail ear openings n in the rotary feed hopper N at the lower segment of the rotary feed hopper adjacent to the feed chute M are preferably closed by a yielding gate or wing P which is curved concentrically with the feed hopper and is preferably hinged to the bottom plate M¹ at p and held in contact with the rotary feed hopper by a spring p¹.

I claim:

1. In a bail ear attaching machine, the combination with upper and lower seaming devices, of a horn, a reciprocating feed slide

on said horn for the bail ears, a feed chute for the bail ears and a rotating feed hopper for the bail ears, furnished with bail ear openings in its peripheral wall at the lower edge thereof, substantially as specified.

2. In a bail ear attaching machine, the combination with a horn and upper and lower bail ear clenching dies, the latter being mounted on the horn and a feed chute, of a rotating feed hopper furnished with bail ear openings in its peripheral wall at its lower edge, and a feed slide on said horn for pushing the bail ears one by one from the feed chute into position between said dies, substantially as specified.

3. In a bail ear attaching machine, the combination with a horn and upper and lower bail ear clenching dies, the latter being mounted on the horn and an inclined feed chute, of an inclined rotating feed hopper having bail ear openings in its peripheral wall at its lower edge, and a feed slide on said horn for pushing the bail ears one by one from the feed chute into position between said dies, substantially as specified.

4. In a bail ear attaching machine, the combination with a horn and upper and lower bail ear clenching dies, the latter being mounted on the horn and an inclined feed chute, of an inclined rotating feed hopper having bail ear openings in its peripheral wall at its lower edge, said feed chute having a segmental curved bail ear receiving pocket at its upper edge and a feed slide on said horn for pushing the bail ears one by one from the feed chute into position between said dies, substantially as specified.

5. In a bail ear attaching machine, the combination with a horn and upper and lower bail ear clenching dies, the latter being mounted on the horn and an inclined feed chute, of an inclined rotating feed hopper having bail ear openings in its peripheral wall at its lower edge, said feed chute having a segmental curved bail ear receiving pocket at its upper end furnished with a yielding cover, substantially as specified.

6. In a bail ear attaching machine, the combination with a horn and upper and lower bail ear clenching dies, the latter being mounted on the horn and an inclined feed chute, of an inclined rotating feed hopper having bail ear openings in its peripheral wall at its lower edge, said feed chute having a segmental curved bail ear receiving pocket at its upper end and a yielding gate at the lowermost end of said curved pocket, substantially as specified.

7. In a bail ear attaching machine, the combination with upper and lower seaming devices, of a reciprocating feed slide for the bail ears, a feed chute for the bail ears, a rotating feed hopper for the bail ears, furnished with bail ear openings and a feed device for supplying the liquid packing or

lacquer to the seam before the flanges thereof are seamed together by the dies, substantially as specified.

8. In a bail ear attaching machine, the combination with a horn, of a die thereon, means for feeding liquid packing to the bail ear in the die on the horn, a feed slide for the bail ears, an upper die, a slide for operating the upper die, a feed chute for delivering the bail ears to the bail ear feed slide, and a rotary feed hopper having openings in its peripheral wall at the lower edge thereof for delivering the bail ears to the feed chute, substantially as specified.

9. In a bail ear attaching machine, the combination with a horn, of a die thereon, means for feeding liquid packing to the bail ear in the die on the horn, a feed slide for the bail ears, an upper die, a slide for operating the upper die, a feed chute for delivering the bail ears to the bail ear feed slide, and a rotary feed hopper having openings in its peripheral wall at the lower edge thereof for delivering the bail ears to the feed chute, said feed chute having a curved pocket adjacent to said rotary feed hopper, substantially as specified.

10. In a bail ear attaching machine, the combination with a horn, of a die thereon, means for feeding liquid packing to the bail ear in the die on the horn, a feed slide for the bail ears, an upper die, a slide for operating the upper die, a feed chute for delivering the bail ears to the bail ear feed slide, and a rotary feed hopper having openings in its peripheral wall at the lower edge thereof for delivering the bail ears to the feed chute, said feed chute having a curved pocket adjacent to said rotary feed hopper provided with a yielding cover, substantially as specified.

11. In a bail ear attaching machine, the combination with a horn, of a die thereon, a feed slide for the bail ears, an upper die, a slide for operating the upper die, a feed chute for delivering the bail ears to the bail ear feed slide, and a rotary feed hopper having openings therein for delivering the bail ears to the feed chute, said feed chute having a curved pocket adjacent to said rotary feed hopper, said curved pocket having a yielding gate at the end thereof adjacent to the feed chute, substantially as specified.

12. In a bail ear attaching machine, the combination with a horn, of a die thereon, a feed slide for the bail ears, an upper die, a slide for operating the upper die, a feed chute for delivering the bail ears to the bail ear feed slide, and a rotary feed hopper having openings in its peripheral wall at the lower edge thereof for delivering the bail ears to the feed chute, said die on the horn having a cavity to receive and surround the bail ear and its assembled cap prior to the application of the pail body thereto, and

means for feeding liquid packing to the bail ear in the cavity of said die on the horn, substantially as specified.

13. In a bail ear attaching machine, the combination with a horn, of a die thereon, a feed slide for the bail ears, an upper die, a slide for operating the upper die, a feed chute for delivering the bail ears to the bail ear feed slide, a rotary feed hopper having 10 openings in its peripheral wall at the lower edge thereof for delivering the bail ears to the feed chute and a feed device for supplying a liquid packing to the bail ear flanges before the dies operate to attach the bail 15 ear to the pail body, substantially as specified.

14. The combination with a horn and upper and lower bail ear clenching dies, the latter being mounted on the horn and an 20 inclined feed chute, of an inclined rotating feed hopper, furnished with a series of discharge openings in its peripheral wall at its lower edge, and a feed slide on said horn for pushing the bail ears one by one from the feed chute into position between said 25 dies, substantially as specified.

15. The combination with a horn and upper and lower bail ear clenching dies, the latter being mounted on the horn and an 30 inclined feed chute, of an inclined rotating feed hopper, furnished with a series of discharge openings in its peripheral wall at its lower edge, said feed chute having a curved guide at its upper end forming a 35 segmental pocket concentric with the rotating feed hopper, and a feed slide on said horn for pushing the bail ears one by one

from the feed chute into position between said dies, substantially as specified.

16. The combination with a horn and upper and lower bail ear clenching dies, the latter being mounted on the horn and an inclined feed chute, of an inclined rotating feed hopper, furnished with a series of discharge openings in its peripheral wall at its 45 lower edge, said feed chute having a curved guide at its upper end forming a segmental pocket concentric with the rotating feed hopper and a yielding cover for said segmental pocket, substantially as specified. 50

17. The combination with an inclined feed chute, of an inclined rotating feed hopper, furnished with a series of discharge openings at its lower edge, said feed chute having a curved guide at its upper end 55 forming a segmental pocket concentric with the rotating feed hopper, a yielding cover for said segmental pocket and a yielding gate at the end of said pocket adjacent to the feed chute, substantially as specified. 60

18. The combination with an inclined feed chute, of an inclined rotating feed hopper, furnished with a series of discharge openings at its lower edge, said feed chute having a curved guide at its upper end 65 forming a segmental pocket concentric with the rotating feed hopper, and a yielding gate at the end of said pocket adjacent to the feed chute, substantially as specified.

SWAN TEVANDER.
